ATTORNEY.

UNITED STATES PATENT OFFICE.

FREDERICK M. HOLMES, OF SPRINGFIELD, MASSACHUSETTS.

TWINE CUTTING AND RETAINING DEVICE.

1,138,756.

Specification of Letters Patent.

Patented May 11, 1915.

Application filed March 14, 1913. Serial No. 754,213.

To all whom it may concern:

Be it known that I, FREDERICK M. HOLMES, a citizen of the United States of America, and resident of Springfield, in the county of 5 Hampden and State of Massachusetts, have invented certain new and useful Improvements in Twine Cutting and Retaining Devices, of which the following is a full, clear, and exact description.

10 The object of this invention is to provide, as an attachment on the edge portion of a counter in a store, or on other support, a device of extremely simple and inexpensive construction through which twine from a 15 ball or supply located beneath the counter may freely run as it is to be used but which device is operative, automatically, as a retainer for the twine preventing the upper or free end portion thereof from falling 20 down below the counter, rendering it inconvenient for the clerk from time to time to recover it.

The invention is described in conjunction 25 with the accompanying drawing and is defined in the claim.

In the drawing, in which the device is shown considerably enlarged,—Figure 1 is a plan view of the retainer as applied for use at the edge of a counter. Fig. 2 is a 30 sectional elevation of the device with the movable member thereof as in its position of operative effect. Fig. 3 is a side elevation showing the movable member as upwardly and rearwardly swung, as is advantageously done at a time when the twine 35 is to be threaded through the device. Fig. 4 is a side elevation provided for the purpose of showing that the device may be supported in a depending as well as in a horizontally 40 projecting position.

In the drawing, A represents a frame comprising opposite parallel side members *a*, a, transverse uniting member *b*, and laterally extending attachment lugs *d* through which 45 by screws *f* the frame is to be secured at the edge portion of a counter or other support.

The frame formed as described has the comparatively long and narrow aperture *g* 50 which is open from edge to edge of the frame and within such aperture a member B is connected by pivot *h*, the point of pivotal connection being well toward what is here regarded as the rear or attachment end 55 of the frame. Said member has its end portion *j* which is the farther from the pivot

formed eccentric to such pivot or cam shaped and is coöperative for twine binding effect with the adjacent end wall *b* of the frame. The said pivoted member has its eccentric 60 edge of serrated character or formed with fine ratchet shaped teeth *i* to increase the certainty of binding effect.

One of the side walls *a* of the frame has a slit opening *m* therethrough, at a suitable 65 location forward of the pivot *h* for facilitating the threading of the twine through the device,—the pivoted member B being upwardly and rearwardly swung at such time as indicated in Fig. 3.

70 The pivoted member has a back *o* which is inclined to the general length of such member; and the member is provided at its intermediate portion or shank with a transverse perforation *t*.

D represents a cutter blade provided with a stem or shank member *u* which is engaged through said perforation and immovably held therein by having a tight driving fit. The cutting edge of the blade is directed 80 opposite from the eccentric formed edge of the pivoted member, that is rearwardly and it is forwardly and upwardly inclined more or less conformable to the aforementioned inclined back of the member D, and against 85 which the blade closely lies. The blade is of such extent as to protrude out beyond the margin of the aperture in the frame so as to present a readily accessible cutter for the twine and enabling the clerk to conveniently sever the latter from time to time 90 as occasion requires.

As manifest, the strain imparted by the twine against the cutter for the severing of the twine increases the tension or binding 95 effect of the pivoted member against the twine which is disposed between the forward edge of such member and the frame wall *b*.

As apparent, on an inspection and comparison of Figs. 2 and 4, the eccentric ended member D is so shaped and hung on its pivot in the apertured frame that by gravitational effect it will exert its twine engagement action whether the device is in a horizontally 105 projecting position with reference to the edge of the counter or in a depending relation to the counter.

As to be perceived from the drawing, the device consists of a minimum of parts which 110 are of simple character, most cheaply produced, and easily assembled, and the device,

moreover, is susceptible of utilization for an indefinite time without derangement or necessity of repair.

I claim:—

- 5 A twine retaining device comprising a frame having a comparatively narrow aperture therein and having attachment lugs for the connection of the frame to a counter, a member having a pivot connecting it with-
10 in the rear portion of the apertured frame, having its end portion farther from the pivot formed eccentric to such pivot and co-operative for twine binding effect with the adjacent end wall of the frame, and said

pivoted member having a back inclined to the general length of such member, and a cutter secured to the pivoted member whereby the edge of the blade is directed opposite from the eccentric formed edge of said pivoted member, and conformed to the afore- 20 said inclined back.

Signed by me at Springfield, Mass., in presence of two subscribing witnesses.

FREDERICK M. HOLMES.
